UNITED STATES PATENT OFFICE

162,993

BOTTLE CLOSURE OR THE LIKE

William Satz, Los Angeles, Calif.

Application January 5, 1951, Serial No. 13,674

Term of patent 7 years

(Cl. D58—26)

To all whom it may concern:

Be it known that I, William Satz, a citizen of the United States of America and a resident of Los Angeles, California, have invented a new, original, and ornamental Design for Bottle Closure or the like, of which the following is a specification, reference being had to the accompanying drawing, forming a part hereof.

I claim:

The ornamental design for a bottle closure or the like, substantially as shown and described.

WILLIAM SATZ.
